UNITED STATES PATENT OFFICE

91,678

DESIGN FOR A COMBINATION INK CONTAINER AND DISPENSER

Edward Lundeen, Rock Island, Ill., assignor to Capital Ink Machine Company, Springfield, Ill.

Application November 27, 1933, Serial No. 49,880

Term of patent 7 years

To all whom it may concern:

Be it known that I, EDWARD LUNDEEN, a citizen of the United States, residing at Rock Island, in the county of Rock Island and State of Illinois, have invented a new, original, and ornamental Design for a Combination Ink Container and Dispenser, of which the following is a specification, reference being had to the accompanying drawing, forming a part thereof.

In the drawing:—

Fig. 2 is a front elevation thereof.

Fig. 3 is a plan view thereof.

What I claim is:—

The ornamental design for a combination ink container and dispenser, as shown.

In testimony whereof, I affix my signature.

EDWARD LUNDEEN.
